UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. **11,397**, dated September 9, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

The principal figure, A, of this carpet is nearly square in outline; but its outline is not complete, being merely indicated by the corners of the square. This figure A is richly decorated with representations of fern-leaves *a*, roses *b*, and other flowers. The leaves and some of the flowers project over the margin of the figure A. At one side the figure is surmounted by a

pointed figure, B; at the opposite side by a double-pointed figure, C. Smaller rectangles D and E and a polygonal figure, F, are also formed on the background and embraced by appropriate borders. All the figures are decorated with floral embellishments, as shown.

I claim—

1. The design for a carpet, consisting of the figure A, having leaves *a* and flowers *b*, substantially as shown.

2. The design for a carpet, consisting of the figures A, B, and C, substantially as shown.

3. The design for a carpet, consisting of the figures A, B, C, D, E, and F, substantially as shown.

The above specification of my invention signed by me this 30th day of July, 1879.

HENRY HORAN.
